SEAT SUPPORT

Walter E. Nordmark and Donald S. Huhta, Grand
Rapids, Mich., assignors to American Seating
Company, Grand Rapids, Mich., a corporation
of New Jersey

Application December 16, 1949, Serial No. 133,378

3 Claims. (Cl. 155—94)

1

The present invention relates to seat supports and more particularly to vertically adjustable supports for seats of the type provided for the operators of motorbusses, railway engines and the like.

The primary objects of the invention are to provide an improved seat for the drivers of vehicles, which may easily and readily be adjusted for height according to the requirements and preferences of the particular driver occupying the seat; to provide such a seat support having means for counterbalancing the seat so that it may be moved up and down with a minimum of effort to a desired position of vertical adjustment; to provide such a seat support in which, when the seat is adjusted and occupied, the seat load is transmitted to the base through strong and durable connections; and in general to provide a seat structure and support which is simple in construction, efficient in use, reasonably economical in manufacture, and attractive in appearance.

An illustrative embodiment of the invention is shown in the accompanying drawings, wherein:

Figure 1 is a perspective view of a typical driver's seat mounted upon the seat support or pedestal of the present invention;

Figure 2 is a perspective view of the pedestal per se, a cover member thereof having been removed;

Figure 3 is a central, vertical sectional view of the seat pedestal taken on line 3—3 of Figure 5 and showing the seat fragmentarily and the depending seat column being inserted into the base of the supporting structure;

Figure 4 is a sectional view similar to Figure 3 and showing the seat and column in a lowered position of vertical adjustment; and

Figure 5 is a horizontal sectional view of the same taken on line 5—5 of Figure 4.

Referring now in detail to these drawings, the driver's seat shown in Figure 1 comprises a conventional upholstered seat 10 and back 11 mounted on a tubular frame 12 which is in turn secured to the seat bracket 13 (see Figures 3 and 4), and the connections between the seat and seat bracket are such as to provide for forward and rearward adjustment and seat tilt adjustment. The latter connections are not shown in detail nor designated by numbers inasmuch as they form no part of the present invention. A depending tubular column 14 is secured as by welding to the underside of the seat bracket 13 and said column provides the means whereby the seat is connected to the seat support or pedestal generally designated 15 and hereinafter more fully described.

2

The supporting pedestal 15 comprises a base plate 16 having apertures therethrough for the accommodation of bolts 17 by means of which the structure is secured to the floor of a vehicle or the like, a base 18 secured as by welding to the bottom plate 16, and a cap 19 secured as by welding to the top of the base 18. The base 18 comprises a sheet of metal bent to form a generally conical lower base portion 20 continuing upwardly in the rear to form a generally semi-conical rear upper base portion 21, and the opposite sides of the front upper base portion are turned inwardly and then forwardly to form upright supporting flanges 22, and finally outwardly. The cap 19 is provided with a keyhole aperture 23 in its rearward portion, said aperture being surrounded by a downwardly turned flange 24 thus forming a vertical bearing. A shelf 25 has a downwardly turned peripheral flange 26 which is secured to the inner surface of the base 18 as by welding, said shelf being positioned intermediate the base plate 16 and the cap 19 and being provided with a keyhole aperture 27 surrounded by a downwardly turned flange 28 thus to form a vertical bearing in vertical alignment with the bearing in the cap 19, these two bearings thus defining in effect a single vertical slide bearing cavity in the base 18.

The tubular column 14 on the seat vertically 30 slidably bears in the circular portions of the key-hole apertures 23, 27 which define the base's vertical slide bearing cavity above described, and said column 14 is provided on its forward external surface with a rack bar 29. This rack bar 29 is 35 of channel-iron formation, having a web portion 30 secured to the column 14 as by welding, and forwardly extending flanges 31 each having a vertical series of teeth 32. The channel rack bar 29 travels with the column 14 in the key portions 40 of the apertures 23, 27 which define the base's vertical slide bearing cavity, and in the keyway 33 formed between the upright supporting walls or flanges 22 of the base. These supporting walls or flanges 22 are provided with non-vertical, 45 rearwardly-downwardly inclined slots 34 in horizontal alignment with each other, and a horizontally disposed detent pin 35 has its opposite end portions movable in said slots so that the detent pin 35 is movable to a position for engagement with the teeth 32 of the rack bar 29 and also to a position out of the path of said rack bar. V-shaped wire springs 36 have their coiled middle portions secured on opposite ends of a mooring pin 37 disposed in aligned openings in the 50 upright flanges 22 of the base, and each spring 55

36 has one of its ends projected through a diametric aperture in the adjacent end of the pin 35 and the other of its ends bearing against the adjacent outwardly flanged portion 38 of the base's upper forward portion. The springs 36 normally urge the pin 35 toward position of engagement with the teeth 32 of the rack bar 29.

Means accessible to the seat occupant are provided for manually—or pedally—moving the pin 35 out of the path of the rack bar 29 thus to permit free up and down movement of the seat and its depending column 14. As here shown these means comprise a lever 39 pivotally mounted on a pin 40 secured to brackets 41 which are fixedly mounted on the base plate 16 as by welding. This lever 39 has an operating arm which extends rearwardly-upwardly through a slot 42 in the shelf 25 and has an aperture at its upper end through which extends the pin 35. The lower arm of the lever 39 extends forwardly through an opening 43 in the base 18 and is provided with a pedal 44 which when depressed turns the lever 39 to thus withdraw the pin 35 from the path of the rack bar. The slots 34 in which the pin 35 moves are desirably made slightly arcuate about the pivot pin 40 of the lever 39 as a center.

A cover member 45 for enclosing the mechanism just described is of generally semi-conical formation, and is secured to the upper rear portion of the base as by means of machine screws 46 (see Figure 1). This cover member 45 completes the substantially conical contour of the base thus enhancing the appearance of the base, and the cover member may be quickly removed for inspection or replacement of parts of the mechanism.

A stiff coiled compression spring 47 is disposed within the tubular column 14 and bears against the base plate 16 and the seat or seat bracket 13. This spring 47 counterbalances the seat to facilitate upward movement thereof during adjustment, but the spring is not quite strong enough to force the unoccupied seat upwardly without slight additional manual force.

When the seat and its depending column 14 are assembled to the supporting base or pedestal, the column is inserted in the vertical slide bearing of the base and lowered into position. During this assembly a cammed surface 48 on the lower end of the rack bar 29 strikes the pin 35 (see Figure 3) and moves it out of the path of the rack bar so that it is not necessary to depress the pedal 44 when the seat is assembled to the pedestal. After assembly the pedal 44 is depressed whenever it is desired to disengage the pin 35 from the rack bar 29 in order to effect vertical readjustment. A detent tooth 49 is also provided near the lower end of the rack bar 29, which tooth 49 is adapted to engage the pin 35 when the seat is lifted beyond its uppermost position of adjustment so that the seat cannot be completely removed from the pedestal unless the pedal 44 is depressed to disengage the pin 35 from the rack bar's tooth 49.

It will be seen that when the seat is in a properly adjusted position with the pin 35 engaged behind one of the rack bar's teeth 32, the seat load is transmitted through pin 35 directly to the upright supporting walls or flanges 22 of the base 18 and thus to the base. This arrangement is such that a minimum of stress and wear is applied to the various parts of the mechanism. The seat may be quickly and easily adjusted to the height desired by the operator.

It will also be seen that the forward-downward

slope of the notches between the teeth 32, into which notches the pin 35 fits, effects a camming action on the pin 35 when the seat is manually raised, so that the pin is cammed out of the path of the rack bar. Thus the seat may be manually lifted by the operator while seated and without depressing the pedal 44, to a higher position of adjustment.

While but one specific embodiment of the invention has been herein shown and described, it will be understood that numerous details may be altered or omitted without departing from the spirit of the invention as the same is defined by the following claims.

We claim:

1. In a seat structure: a base having a vertical bearing cavity therein of generally keyhole-shaped cross-section, each of the vertical walls at opposite sides of the keyway portion of said bearing cavity having a non-vertical slot therein in horizontal alignment with the slot of the other wall; a seat provided with a depending tubular column vertically slideable in the cylindrical bearing portion of said bearing cavity; a channel rack bar having its web secured to the tubular column and having its flanges extending forwardly into the keyway portion of said bearing cavity and vertically slideable therein with the column, each flange having a vertical series of teeth in horizontal alignment with the teeth of the other flange; a lever mounted pivotally about a horizontal axis on the lower forward part of the base and having a pedal arm extending exteriorly of the base and an operating arm extending rearwardly-upwardly between the flanges of said channel rack bar; a horizontal detent pin on the upper end of said operating arm and extending on both sides thereof for operative engagement with selected pairs of teeth on said channel rack bar's flanges for supporting the seat and its depending column in vertically adjusted position, the opposite extremities of said pin bearing in said slots in the vertical walls at opposite sides of the keyway portion of the bearing cavity for transmitting the seat load from the column to the base.

2. In a seat structure: a base having a vertical bearing cavity therein of generally keyhole-shaped cross-section, each of the vertical walls at opposite sides of the keyway portion of said bearing cavity having a non-vertical slot therein in horizontal alignment with the slot of the other wall; a seat provided with a depending tubular column vertically slideable in the cylindrical bearing portion of said bearing cavity; a channel rack bar having its web secured to the tubular column and having its flanges extending forwardly into the keyway portion of said bearing cavity and vertically slideable therein with the column, each flange having a vertical series of teeth in horizontal alignment with the teeth of the other flange; a lever mounted pivotally about a horizontal axis on the lower forward part of the base and having a pedal arm extending exteriorly of the base and an operating arm extending rearwardly-upwardly between the flanges of said channel rack bar; a horizontal detent pin on the upper end of said operating arm and extending on both sides thereof for operative engagement with selected pairs of teeth on said channel rack bar's flanges for supporting the seat and its depending column in vertically adjusted position, the opposite extremities of said pin bearing in said slots in the vertical walls at opposite sides of the keyway portion of the bearing cavity for

transmitting the seat load from the column to the base; and spring means normally urging said detent pin toward its position of engagement with the teeth of said channel rack bar.

3. In a seat structure: a base having a vertical bearing cavity therein of generally keyhole-shaped cross-section, each of the vertical walls at opposite sides of the keyway portion of said bearing cavity having a non-vertical slot therein in horizontal alignment with the slot of the other wall; a seat provided with a depending tubular column vertically slideable in the cylindrical bearing portion of said bearing cavity; a channel rack bar having its web secured to the tubular column and having its flanges extending forwardly into the keyway portion of said bearing cavity and vertically slideable therein with the column, each flange having a vertical series of teeth in horizontal alignment with the teeth of the other flange; a lever mounted pivotally about a horizontal axis on the lower forward part of the base and having a pedal arm extending exteriorly of the base and an operating arm extending rearwardly-upwardly between the flanges of said channel rack bar; a horizontal detent pin on the 25

5
